(57) CLAIM

I claim the ornamental design for portion control food ware, as shown and described.

DESCRIPTION

FIG. 1 is an upper orthogonal view of the portion control food ware of the present invention.

FIG. 2 is a side view of the portion control food ware of the present invention.

FIG. 3 is a top view of the portion control food ware of the present invention.

FIG. 4 is a lower orthogonal view of the portion control food ware of the present invention; and,

FIG. 5 is an upper orthogonal cross-section thereof taken from line 5-5 in FIG. 1.

The broken lines depict environmental subject matter and form no part of the claim.
